ABSTRACT OF THE DISCLOSURE

A sound system for an electrical organ includes a cabinet chamber through which sound is projected into a listening area by one or more loudspeakers. A pair of sound-reflecting baffles or vanes are rotated within the chamber at unequal speeds to produce a full, enveloping and non-pulsating sound.

The present invention relates to acoustical apparatus, and has for a primary object the provision of an improved sound projecting system for electrical organs, although the principles of the invention are applicable to other types of sound systems.

Electrical organs of several types are known, and have become increasingly popular because of their convenience, small size and reasonable cost. It is desirable that such organs be able to imitate as closely as possible the sounds produced by a pipe organ, and in large part they are successful in doing so. By producing, combining and regulating various tones electronically and/or mechanically, most electrical organs are capable of producing a sound which is quite similar to the sound produced by an organ pipe.

Although electrical organs can reproduce the sound of individual pipe organ tones or notes, nevertheless they have not been able to reproduce the overall sound or effect of a pipe organ. A pipe organ, of course, is ordinarily installed in a large space, and includes many sound sources spread over a large area. As a result, a pipe organ produces a "big," full sound having a largely omnidirectional effect upon a listener. The sound from the pipe organ thus seems to surround or envelope the listener.

Since the sound from electrical organs is projected from one or more loudspeakers, the sound, particularly in the middle and high frequency ranges, is highly directional. Thus, the listener hears the sound from a single point or region and the full sound of a pipe organ is lost. Some attempts have been made to overcome this problem, notably by the design of the loudspeaker enclosure or cabinet, by the use of several speakers, and by the use of various baffle arrangements. Known methods, however, have not been satisfactory and often are expensive. Arrangements using one or more moving speakers or baffles have been used to achieve a rhythmic, pulsating, tremolo effect, but such arrangements have not eliminated the objectional directional characteristic of electrical organ sounds.

It is therefore one important object of the present invention to provide novel acoustical apparatus for improving the sound produced by electrical organs or other sound producing devices.

More particularly, it is an object of the invention to provide a novel sound system for eliminating or reducing the directional characteristic of the sound of an electrical organ, thereby to "enlarge" the sound so that the sound of a pipe organ is more closely simulated.

Another object is to provide an apparatus and method for projecting or distributing the sound from an electrical organ in a random and moving manner.

A further object of the invention is to provide novel acoustical apparatus that can economically and conveniently be added to an organ loudspeaker unit greatly to improve the sound quality thereof.

2

In brief, the above and other objects and advantages of the present invention are achieved in one embodiment of the invention through the provision of an organ sound system including one or more loudspeakers projecting organ sound into a listening area by way of a speaker cabinet or enclosure. In accordance with an important feature of the invention the sound is projected throughout the listening area in a random and moving manner to create a full, enveloping, non-pulsating effect by means of a pair of vanes positioned in the sound path within the enclosure and rotated at unequal speeds.

A more complete understanding of the invention together with its objects and advantages may be had from the following detailed description of certain embodiments 15 of the invention taken together with the accompanying drawing, in which:

FIG. 1 is a perspective view of the speaker unit of an organ sound system constructed in accordance with the features of the invention, with part of the cabinet broken away;

FIG. 2 is a sectional view taken along the line 2—2 of FIG. 1;

FIG. 3 is an enlarged view of a control unit for the system;

FIG. 4 is a schematic representation of a circuit for controlling the system; and

FIG. 5 is a sectional view similar to FIG. 2 and illustrating an alternative embodiment of the present invention.

Referring now to the drawing, there is illustrated an improved organ sound system embodying the features of the present invention and including a speaker unit generally designated as 12 (FIGS. 1 and 2) together with a control unit generally designated as 14 (FIG. 3). The speaker unit 12 is adapted to be positioned in a room or other listening area and interconnected to receive audio frequency electrical signals from an electrical organ console and amplifier in the usual manner. In accordance with the invention, the speaker unit 12 is provided with a novel acoustical apparatus generally designated as 16 and described in detail below. The apparatus 16 is controlled by the control unit 14 which may be conveniently mounted beneath the organ console keyboard 18.

Proceeding now to a description of the speaker unit 12, this unit includes a cabinet or enclosure 20 which may be fabricated of wood in the usual manner. An interior wall 22 subdivides the inside of the cabinet 20 into two chambers 24 and 26 intercommunicating by way of an opening 28 in the wall 22. Audio frequency signals are supplied from the electrical organ console and amplifier through suitable wires (not shown) to an electro-acoustical transducer in the form of a loudspeaker 30 mounted in the chamber 24 on the wall 22 for projecting sound through the opening 28 and into the chamber 26. The cabinet 20 includes front and side openings 32 and 34 covered by grille cloth 36 for allowing sound to escape from the chamber 26 into the listening area, although a front opening or openings alone could be used.

Conventional electrical organs suffer from the difficulty that the sound, especially in the middle and higher frequency ranges, is quite directional. Thus, throughout the listening area the listener hears these sounds principally from the direction of the loudspeaker, and the full, enveloping sound of a pipe organ is absent.

In accordance with an important feature of the present invention, the acoustical apparatus 16 includes a pair of baffle members or vanes 38 and 40 moving at unequal speeds for projecting and distributing the sounds from the speaker 30 in a random and moving manner throughout the listening area. This arrangement of at least two moving baffles operating at unequal speeds provides a full, enveloping, and non-pulsating sound and reduces

or eliminates the directional characteristic suffered with conventional electrical organs.

More specifically, the vanes 38 and 40 are mounted in side-by-side relation in the chamber 26 and thus each vane is in the path of sound travelling from the speaker 30 through the openings 32 and 34 to the listening area. The vanes may be constructed of various materials, such as sheet steel or wood, having sound reflecting properties. The vanes are mounted for rotation about parallel vertical axes by virtue of being attached to a pair of spaced, rotatable drive shafts 42 and 44 by brackets 46. The shafts 42 and 44 are drivingly connected to a pair of drive motors 48 and 50 carried on a support shelf 52 mounted on the inner wall 22.

Although many possible arrangements may be used for rotating the vanes 38 and 40 at unequal speeds, in FIG. 4 there is illustrated one control circuit, generally designated as 54, for controlling the operation of the drive motors 48 and 50. As there illustrated, the drive motor 48 is connected in series with an on-off switch 56 between the terminals of a suitable electrical connector 58 adapted to be connected to a suitable power supply, such as an outlet associated with the organ console and controlled by the main organ on-off switch. Whenever the circuit 54 is energized and the switch 56 is closed, the motor 48 operates at a predetermined speed depending upon its design. In order to control the operation of the second motor 50, the motor is connected in series with an on-off switch 60 and also with a speed regulating device 62 which may be of any known construction. When the control circuit 54 is energized and the switch 60 is closed, the motor 50 operates at a speed determined by the motor design and also by the setting of the speed regulating device. Conveniently the manually operated controls of the circuit 54, i.e., the on-off switches 56 and 60 and the speed control 62, are mounted on a control panel 64 positioned on the organ console as illustrated in FIG. 3 so as to be convenient to the player of the organ. Alternatively, of course, the controls may be associated with the speaker unit 12.

It can now be seen that the control circuit 54 is capable of operating the drive motors at unequal speeds by adjustment of the speed control 62. It has been found in devices constructed in accordance with the invention that greatly improved sound quality is obtained when a plurality of baffles or vanes in the sound path are operated in this manner. More specifically, the directional characteristic of the sound from the loudspeaker is overcome, and a full, enveloping sound is heard, without a pulsating tremolo.

Although there may be other factors creating this greatly improved sound quality, it is believed that the improvement is due at least in part to the reflection of sound waves within the cabinet chamber 26 and to interaction between the vanes moving at unequal speeds. It is known that the use of a single rotating vane produces merely a tremolo effect without elimination of the directional characteristic. However, when two vanes are moved at different speeds, a very different effect is obtained because there is no pulsating, tremolo effect and the directional characteristic is eliminated or reduced. It is believed that the ever-changing angles between the two vanes and between the vanes and the walls causes the sound to be inter-reflected in a continuously varying "random" pattern within the enclosure and from the enclosure into the listening area.

Another embodiment of the invention is illustrated in FIG. 5 wherein there is shown a speaker unit 12' similar to the speaker unit 12 except that it uses a pair of loudspeakers 66 and 68 rather than a single loudspeaker. It has been found that like the embodiment of FIGS. 1-4, the arrangement of FIG. 5 produces a full, enveloping sound when the vanes are rotated at unequal speeds.

In one system constructed in accordance with the invention, very satisfactory results were obtained by rotat-

ing one of the vanes at approximately 30 revolutions per minute and rotating the other vane at approximately 35-50 revolutions per minute. These figures are given by way of example only and are not intended to limit the scope of the invention as defined in the claims.

One advantage of the system of the present invention is that the speaker unit 12 can be used as the only speaker unit associated with the organ console. Thus, if the switches 56 and 60 are both open the unit 12 functions in the conventional manner. If only the switch 60 is closed the vane 40 is rotated while the vane 38 remains stationary and a tremolo or pulsating sound is achieved. Operation of the speed control 62 determines the speed of rotation of the vane 40, thereby to regulate the speed or frequency of the tremolo effect.

The system of the present invention is also well-suited for use with a reverberation unit of any type, such as a spring-delay line unit or a magnetic tape unit. When the vanes 38 and 40 are moved at different speeds and a reverberation unit is included in the system, an exceedingly realistic "concert hall" sound can be achieved.

An important advantage of the apparatus of the present invention is that it can conveniently be added to existing organ speaker units. As will be apparent to those skilled in the art, this can be accomplished either by modification of the existing speaker cabinet to provide a van containing chamber receiving sound from the speaker, or by the use of a separate, auxiliary cabinet placed in front of the existing cabinet.

While the present invention has been described in connection with the details of certain specific embodiments, other embodiments and equivalents may be devised which fall within the spirit and scope of the invention. Consequently, it should be understood that the invention is not limited by details of the described embodiment except as set forth in the following claims.

What is claimed as new and desired to be secured by Letters Patent of the United States is:

1. Acoustical apparatus for use with a loudspeaker system of an electrical organ or the like of the type including an enclosure, electro-acoustical transducer means for projecting sound into the enclosure, and at least one opening in the enclosure for allowing sound to escape from the enclosure into a listening area, said acoustical apparatus comprising first and second baffles supported within said enclosure, each in the path of sound waves traveling from the transducer means to the listening area, first means for moving the first baffle at a first speed, and second means for moving the second baffle at a second speed unequal to the first speed.

2. The acoustical apparatus of claim 1, said first and second moving means including a first drive motor connected in driving relation to the first baffle, a second drive motor connected in driving relation to the second baffle, and a motor control circuit connected to both said motors for operating said motors at different speeds.

3. The acoustical apparatus of claim 2, said motor control circuit including an adjustable speed controlling device in circuit with said first drive motor.

4. The acoustical apparatus of claim 1, each of said baffles including a substantial surface area having sound reflecting properties, said baffles being mounted in sound inter-reflecting relationship with one another.

5. The acoustical apparatus of claim 1, each said baffle comprising a substantially planar vane, a pair of parallel drive shafts one connected to each vane, and said first and second moving means including means for rotating said shafts at different speeds.

6. An acoustical system for an organ and the like comprising:
a housing defining a chamber;
means including a loudspeaker for introducing sound waves into said chamber;
an opening in said housing permitting sound waves to escape from said chamber;

first and second baffle members mounted for movement within said chamber; and means for moving said baffle members simultaneously at different speeds thereby to produce a changing distribution of sound from said housing without tremolo.

7. The acoustical system of claim 6, said baffle members each comprising a substantially planar vane.

8. The acoustical system of claim 7, said vanes being mounted for rotational movement around parallel axes.

9. A method of improving the effect of sound produced by an electrical organ and the like comprising the steps of:

projecting the sound from a speaker through a chamber to the listening area;

rotating a first sound reflecting baffle member within the chamber at a first speed;

and rotating a second sound reflecting baffle member within the chamber at a second speed different from said first speed.

10. Acoustical apparatus for use with a loudspeaker system of an electrical organ or the like of the type in-

5

10

20

cluding an enclosure including wall means dividing the enclosure into first and second intercommunicating chambers, a loudspeaker mounted in the first chamber for projecting sound into the second chamber, and at least one opening in the enclosure for allowing sound to escape from the second chamber into a listening area, said acoustical apparatus comprising first and second substantially rectangular and planar vanes formed of sound reflecting material, mounting means supporting said first and second vanes in side-by-side relation within the second chamber for rotation about parallel axes, and drive means drivingly related to said first and second vanes for simultaneously rotating said vanes at different speeds.
